BARREL STAVE CROZER

Jesse W. Leonard, Willard R. Butterworth, Jr.,
 Claud Leonard, Harry A. Wellford, and Walker
 L. Wellford, Jr., Memphis, Tenn.

Application October 22, 1936, Serial No. 106,938

11 Claims. (Cl. 147—18)

This invention relates to improvements in barrel stave crozers and has particular reference to means and methods for duplicating an imperfect stave which it has been found necessary to remove from a barrel because of some deficiency or fault which has shown up under test.

In the manufacture of barrels, particularly those used for holding liquids, stave stock is steamed and bent and from such bent stock, staves of substantially uniform thickness are cut to the proper curvature in cross-section for the particular run of barrels to be made. The stock from which the staves are so cut, is of random width and the side edges of the staves are cut to secure from the stock the maximum available widths, the resulting staves being like the stock, of random widths.

From these staves a barrel shell without heads, is assembled and the staves temporarily secured by heavy iron rings, these rings being forced on the staves to securely and tightly hold them together, and thereafter such treatment as charring, or coating with various preparations, is given the interior of the shell.

The shell thus made ready is then placed in a machine known as a crozer which cuts the shell to the desired length, bevels the inner surfaces of the ends of the staves and cuts certain grooves therein adjacent each of the two ends, the deepest of the grooves at each such end being designated a "croze" and being adapted to receive and hold a head of the barrel. After crozing, the rings adjacent the ends of the barrel are loosened, heads placed and secured by tightening the rings, the exterior of the barrel turned or otherwise finished and the rings replaced with the usual metal hoops.

After completion the barrel is tested under steam pressure or otherwise, to determine whether it be leak proof or not. Should the test of a barrel show that a stave is faulty, it is necessary to replace the stave, or throw the entire barrel away. It is found in this replacement that in spite of all care in the manufacture of the barrels that there are individual differences in the length of the staves from barrel to barrel and that not only must a replacement stave of identical width be selected but the length of the stave must be individual, if a tight barrel is to be secured.

To provide stock for replacement, it is customary after the shells have had interior treatment to select at random a number of these shells and to croze them at one end only, these replacement shells being then knocked down and the

staves placed in stock. When a barrel with a faulty stave shows up, it is shunted to the replacement division with the faulty stave marked. The hoops are loosened, the faulty stave and one head are removed and a replacement stave of substantially identical width is selected from the replacement stock. It has then been customary to place this selected stave in the barrel with its crozed end engaging the barrel head not removed and to tighten the hoops, first at the 10 crozed end and thereafter at the unfinished end. After this is done hand tools are used to cut the stave to length, bevel the end and groove and croze the stave to correspond with the original staves of the barrel, the head being then 15 replaced finished up and retested. It is found however that there is a tendency to enlarge and possibly deepen the croze in the part of the barrel which was not replaced and an additional chance for leakage is introduced.

It is the purpose of the present device to reproduce in replacement staves grooves and particularly a croze which is identically positioned and otherwise identical with the croze in the original stave which is to be replaced.

The objects of the present invention are:

To provide means and methods for reproducing replacement staves which are substantially identical with a stave which has been removed.

To provide means for positioning and holding 30 a stave for crozing and means for crozing the stave.

The means by which these and other objects are accomplished and the manner of their accomplishment will readily be understood from 35 the following description, on reference to the accompanying drawings, in which,—

Fig. 1 is a side elevation of the machine.

Fig. 2 is an end elevation.

Fig. 3 is a sectional elevation taken on the line 40 III—III of Figs. 1 and 5.

Fig. 4 is a sectional elevation taken on the line 4 IV—IV of Figs. 1 and 5.

Fig. 5 is a fragmentary sectional elevation taken on the line V—V of Fig. 4; and

Fig. 6 is a section taken on the line VI—VI of Fig. 4.

Referring now to the drawings in which the various parts are indicated by numerals, 9 is a bed plate supported as by legs 10. 11 is a frame 50 mounted on the bed plate and 12 a slide adjustably mounted in the frame, 13 being an adjusting screw by means of which the slide 12 may be raised or lowered. 14 is a member forming a portion of the slide, from which member ex- 55

cylindrical arm 15 rigidly extends. Turnably mounted on the arm 15 is a motor support 16, to which a motor 17 is secured. 18 are bearings suitably secured to the support 16, and in which 5 bearings a shaft 19 is journaled, this shaft carrying a crozing head 20, which has blades 21, 22, 23, and 24 adapted respectively to cut off the end, bevel the end, form an arcuate groove adjacent the bevel and cut the croze in the stave. 10 Heads of this type being well known and purchasable in the open market, no attempt has been made to show the detail of the head construction.

25 is a belt pulley on the shaft of the motor 17, 26 a pulley on the shaft 19, and 27 a driving belt. 28 is a hand lever secured to the support 16 by means of which the support 16 and the head 20 carried thereby together with the other incidental parts may be shifted around the arm 15. 29 is a counterweight.

30 is a cradle for one end of the staves which cradle is rigidly secured to one end of the bed plate 9 as by the stud 31 and nut 32, this support being positioned in alignment with the croze cutter 24 of the head 20. 33 is a cradle for the middle portion of the staves, this support preferably being adjustably secured to the bed plate as by the stud 34 and nut 35, the stud 34 being movable along a slot 36, extending longitudinally along the center line of the bed plate. 37 is a cradle for 30 the opposite end of the staves this cradle being also secured as by a stud 38 and nut 39, the stud being disposed in a slot 40 extending longitudinally of the bed plate and if desired, forming an uninterrupted continuation of the slot 36, though 35 not so shown.

The cradles 30 and 37 have arcuate seats 41 and 42 respectively, which seats are of identical radius with the outside of the barrel at the crozes, these seats being positioned concentrically below the axial center line of the arm 15. The seat 41 terminates in a radial shoulder 43 and the seat 42 in a similarly radial shoulder 44 against which shoulders the stave 45 to be duplicated is seated. These two shoulders are at equal distances laterally from the longitudinal center line of the machine. 46 is the replacement stave which is to be completed.

47 is a positioning member which is pivotally secured as by a pin 48 to the cradle 30 adjacent 50 the shoulder 43, this positioning member having a blade portion 49, the thickness of the blade being just equal to the width of the croze 50 in one end of the stave 45 which is to be duplicated, and the blade being adapted to snugly engage 55 and seat in the croze of such stave.

The cradle 37 has a pair of upwardly extending arms 51 between which arms a blade 52 is pivotally mounted as on a pin 53, the thickness of this blade being exactly equal to the width of 60 the croze in the opposite end of the stave 45 which is to be duplicated, and to the width of the croze in the corresponding end of the replacement stave 46. 54 are a second pair of lugs disposed opposite the lugs 51 and spaced apart 65 to receive the free end of the blade 52. The cradle 33 has a seat portion with a radius equal to the radius of the center of the barrel, and is adapted to be positioned substantially at the center portion of the staves which are to be 70 worked on. 60, 61, and 62 are stave clamps, the clamps 60 and 62 being ordinarily the only ones used, these two clamps having each an arcuate surface conforming to the radius of the inside of the barrel at a distance below the croze equal 75 to the distance the clamps are positioned from

the croze in the device. Preferably the clamps have teeth 63 which imbed in and firmly grip the staves. If the clamp 61 is used it is formed with a radius conforming to the inner radius of the barrel at the center. Each clamp, as the clamp 5 60, is secured to a depressing member 64 as by a bolt 65, the depressing member being slidably mounted in a shoe 66 secured to the side of the bed plate 9 and extending below such shoe. 67 10 is a foot pedal which is secured to a shaft 68 as by a key 69. Similarly secured to the shaft 68 are arms 70, which arms are connected through links 71 to the member 64.

It will be understood that the various cutters of the crozing head 20 are shaped and set to cut 15 off, bevel, groove, and croze the stave and in exact conformity with the similar work originally done on the staves.

Operation

20

When a barrel has been tested and a stave thereof shown to be faulty, the barrel is loosened up and the faulty stave removed. From the replacement stock a replacement stave of substantially identical width is selected, this stave having 25 one end only crozed. The removed stave, being the stave 45 of the drawings, is positioned in the three cradles 30, 33, and 37 and shoved solidly against the shoulders 43 and 44. The blade 49 is then turned downwardly into the croze 50, the 30 stave being shifted longitudinally until such engagement is possible and can be effected; the foot pedal is then depressed lightly bringing the clamps 60 and 62, and if used, the clamp 61, 35 lightly against the stave. Should the stave 45 be quite narrow as would appear in Fig. 6, the overhanging ends may be blocked up, using for the purpose if desired the replacement stave which is to be worked on. With the faulty stave so held, the cradle 37 is longitudinally shifted 40 until the blade 52 can be seated accurately in the other croze 53A of the stave. Pressure is then released on the clamps, the replacement stave 46 is moved solidly against the stave 45, and the croze in the stave 46 is brought beneath the 45 blade 52, the blade being raised and then seated in the crozes of both staves, to definitely align them. The foot lever 67 is now firmly depressed and the two staves solidly clamped in place. The motor 17 is started and the crozing head 20 50 brought up to speed. After it has attained full speed the hand lever 28 is pulled forward and the cutting knives of the head swung into engagement with the end of the stave 46, the cutters on the head cutting the staves to length 55 beveling, grooving and crozing it at the one operation.

It will be particularly noted, as the cut swings across the stave, that the faulty stave forms a support for the stave which is being cut and 60 prevents under ordinary conditions tearing of the edges of the various cuts.

What we claim is:

1. Means for duplicating in a barrel stave having one end crozed, a second croze, by means of 65 a pattern stave having both ends crozed; said means including a manually shiftable rotary croze cutter, means for driving said cutter, means for constraining said cutter to move in a circular path, means, adapted to be manually engaged with a first croze of said pattern stave, for longitudinally positioning said pattern stave with the croze to be duplicated in alignment with the cutting zone of said cutter and means for supporting said stave with the bottom of said 70 75 75

croze coincident with the circumscribing path of said cutter, said supporting means being adapted to support also said barrel stave to be crozed, means, adapted to be manually engaged with the second croze of said pattern stave and with the croze of said barrel stave, for aligning the crozed end of said barrel stave with the croze at the opposite end of said pattern stave, and means for clamping said pattern and barrel staves during cutting.

2. Means for duplicating in a barrel stave having one end crozed, a second croze, by means of a pattern stave having both ends crozed, said means including a manually shiftable rotary croze cutter, means for driving said cutter, means for constraining said cutter to move in a circular path, means, adapted to be manually engaged with a first croze of said pattern stave, for longitudinally positioning said pattern stave with the croze to be duplicated in alignment with the cutting zone of said cutter, means for supporting the crozed end of said pattern stave, said latter means being adapted to support also said stave to be crozed, means for shifting said cutter to bring the circumscribing path thereof into coincidence with the bottom of said croze of said pattern stave, means for aligning the crozed end of said barrel stave with the other croze of said pattern, and means, adapted to be manually engaged with the second croze of said pattern stave and with the croze of said barrel stave, for clamping said pattern and barrel staves during cutting.

3. Means for duplicating in a barrel stave having one end crozed, a second croze, by means of a pattern stave having both ends crozed; including supporting means, a rotary croze-cutter carried by said means and manually oscillatably thereabout in a circular path, means for driving said croze-cutter, means concentric with said path for supporting said pattern stave with the bottom of the croze therein to be duplicated coincident with the circumscribing path of said croze cutter, said means also supporting the uncrozed end of said barrel stave, means, adapted to be manually engaged with a first croze of said pattern stave, for aligning the croze in said pattern stave with the cutting zone of said cutter, means concentric with said path for supporting the opposite ends of said staves, means adapted to be engaged with the crozes in said opposite ends, for aligning said crozes and means for clamping said staves in said supporting means.

4. Means for duplicating in a barrel stave having one end crozed, a second croze, by means of a pattern stave having both ends crozed; said means including a shaft, a support for said shaft, an arm oscillatably mounted on said shaft and manually shiftable, a rotary croze-cutter carried by the free end of said arm and movable therewith in a circular path, means for driving said croze-cutter, means, concentric with said shaft, for supporting said pattern stave with the bottom of the croze therein to be duplicated coincident with the circumscribing path of said croze cutter, said means also supporting for crozing the uncrozed end of said barrel stave, means, adapted to be manually engaged with a first croze of said pattern stave, for aligning the croze in said pattern stave with the cutting zone of said cutter, means concentric with said shaft for supporting the opposite ends of said staves, means adapted to be engaged with the crozes in said opposite ends for aligning said crozes and means for clamping said staves in said supporting means.

5. Means for duplicating in a barrel stave having one end crozed, a second croze, by means of a pattern stave having both ends crozed; said means including a shaft, a support for said shaft, an arm oscillatably mounted on said shaft and manually shiftable, a rotary croze-cutter carried by the free end of said arm and movable therewith in a circular path, means for driving said croze-cutter, means concentric with said shaft for supporting said pattern stave with the bottom of the croze therein to be duplicated coincident with the circumscribing path of said croze cutter, said means also supporting for crozing the uncrozed end of said barrel stave, means for longitudinally aligning said staves, means, adapted to be manually engaged with a first croze of said pattern stave, for aligning the croze in said pattern stave with the cutting zone of said cutter, means concentric with said shaft for supporting the opposite ends of said staves, means adapted to be engaged with the crozes in said opposite ends for aligning said crozes, and means for clamping said staves in said supporting means.

6. A croze cutter for barrel staves including; a bed plate, a bracket extending upward at one end of said bed plate, a shaft carried by said bracket, a manually shiftable arm oscillatably mounted on said shaft, a rotary head journaled at the free end of said arm and means for driving said head, said head carrying cutters including a croze cutter, cradles mounted on said bed plate, said cradles having arcuate seat portions concentric with said shaft, a pair of aligning blades each of equal thickness with said croze cutter, spaced apart along said bed plate, each said blade being pivotally supported from said bed plate for movement in a zone at right angles to said shaft, one of said aligning members being in the zone of said croze cutter, and being manually movable into the path of said cutter, and removable therefrom during cutting operation, the other of said members being manually movable into aligning position, and retainable therein during said operation, and manually actuatable stave clamps carried by said bed plate and adapted to cooperate with said cradles to hold said staves.

7. A device in accordance with claim 6 in which one of said cradles is positioned in alignment with the zone of said croze-cutter, and another thereof of substantially equal radius is adjustably positioned adjacent the opposite end of said bed.

8. In a barrel stave croze cutter; a bed plate, a bracket extending upward at one end of said bed plate, a shaft carried by said bracket, a manually shiftable arm oscillatably mounted on said shaft, a rotary head journaled at the free end of said arm and means for driving said head, said head carrying cutters including a croze cutter, a pair of cradles mounted on said bed plate, said cradles having arcuate seat portions concentric with said shaft, and of substantially equal radii, and being spaced apart to support opposite end portions of a said stave, and a third cradle of substantially greater radius positioned approximately midway between said spaced cradles, a pair of aligning members each of equal thickness with said croze cutter, spaced apart along said bed plate, each said member being pivotally supported from said bed plate for movement in zones at right angles to said shaft, one of said aligning members being in the zone of said croze cutter, and being manually movable into the

path of said cutter, and removable therefrom during cutting operation, the other of said members being manually movable into aligning position, and retainable therein during said operation, and a pair of manually actuatable clamps carried by said bed plate and adapted to cooperate with said cradles, said clamps being respectively spaced, each between said center cradle and on one of said pair of cradles.

9. In a croze cutter for barrel staves, a bed plate, a bracket extending upward at one end of said bed plate, a shaft carried by said bracket, a manually shiftable arm oscillatably mounted on said shaft, a rotary head journaled at the free end of said arm and means for driving said head, said head carrying cutters including a croze cutter, a pair of cradles mounted on said bed plate, said cradles having arcuate seat portions of substantially equal radius, concentric with said shaft, a first of said cradles being positioned substantially in the zone of said croze cutter and the second thereof being adjustably spaced therefrom adjacent the opposite end of a said stave, a pair of aligning blades each of equal thickness with said croze cutter, one of said blades being pivotally secured to said first cradle in the zone of said croze cutter, and the other thereof being pivotally secured to the second of said cradles, and said first blade being manually movable into the path of said cutter, and removable therefrom during cutting operation, and the other of said members being manually movable into aligning position, and retainable therein during said operation, and manually actuatable clamps carried by said bed plate and adapted to cooperate with said cradles.

10. Means for duplicating in a barrel stave having one end crozed, a second croze, by means of a pattern stave having both ends crozed; in-

cluding supporting means, a rotary croze-cutter carried by said means and manually oscillatable thereabout in a circular path, means for driving said croze-cutter, means concentric with said path for supporting said pattern stave with the bottom of the croze therein to be duplicated coincident with the circumscribing path of said croze-cutter, said means also supporting the uncrozed end of said barrel stave, means, aligned with said croze cutter, for engaging a croze in said pattern stave, means concentric with said path for supporting the opposite ends of both said staves, with said crozes therein in alignment, means adjacent the center of said staves for establishing equal bending in both thereof, and means for clamping said staves in said supporting means.

11. Means for duplicating in a barrel stave having one end crozed, a second croze, by means of a pattern stave having both ends crozed; in-
cluding supporting means, a rotary croze-cutter carried by said means and manually oscillatable thereabout in a circular path; means for driving said croze-cutter; means, engageable with the crozes of said staves, for longitudinally positioning said staves with a said crozed end of both in alignment and with the second said crozed end of said pattern stave in alignment with the cutting zone of said croze-cutter; means for supporting said staves for crozing, and means for clamping said staves, said supporting and clamping means accomplishing equal bending of said staves whereby the length between crozes will be equal in the two.
